MOCCASIN

Gianni Mostile, Via Agnello 2, Milan, Italy

Filed Jan. 27, 1965, Ser. No. 83,607

Term of patent 14 years

(Cl. D7—7)

The figure is a bottom perspective view of a moccasin showing my new design.

The other side of the moccasin has the same appearance as the side shown, and the top of the moccasin is of conventional design.

I claim:

The ornamental design for a moccasin, as shown and described.
